CLAIM

The ornamental design for a combined pet waste container and cover therefor, as shown and described.

DESCRIPTION

FIG. 1 is a perspective view of a combined pet waste container and cover therefor showing my new design;
FIG. 2 is an exploded top plan view;
FIG. 3 is a right side elevational view;
FIG. 4 is a front elevational view with the cover removed;
FIG. 5 is a rear elevational view; and
FIG. 6 is an exploded bottom plan view with the cover tilted slightly.

FIG. 1

FIG. 2

FIG. 3

FIG. 4

FIG. 5

FIG. 6
